A. B. OSTBY

IRON WITH LIGHT AND SWITCH

Filed March 6, 1924

INVENTOR.
ARNE B. OSTBY.
BY HIS ATTORNEY.

James F. Williamson

UNITED STATES PATENT OFFICE.

ARNE B. OSTBY, OF MINNEAPOLIS, MINNESOTA, ASSIGNOR OF ONE-FIFTH TO GEORGE R. DUNN, ONE-TENTH TO ENGEL S. JOHNSON, ONE-TENTH TO EILER S. JOHNSON, ONE-TENTH TO JAMES G. REID, AND ONE-TENTH TO ELSA M. MODROW, ALL OF MINNEAPOLIS, MINNESOTA.

IRON WITH LIGHT AND SWITCH.

Application filed March 6, 1924. Serial No. 697,355.

To all whom it may concern:

Be it known that ARNE B. OSTBY, a citizen of Norway, residing at Minneapolis, in the county of Hennepin and State of Minnesota, has invented certain new and useful Improvements in Irons with Lights and Switches; and he does hereby declare the following to be a full, clear, and exact description of the invention, such as will enable others skilled in the art to which it appertains to make and use the same.

This invention relates to a flat iron or sad iron and particularly to such an iron of the well known electrical type which is heated by electricity. Such irons are commonly provided with a connecting cord with a plug at the end adapted to be received in an electrical socket. It is often desired to use the iron in the evening or after dark when a lamp is necessary. As the plug on the cord preempts the socket, it is often not convenient to have an electric light available unless a double lamp socket is used in the fixture. Even when such a double lamp socket is used, the ironing operation is often at some distance from the fixture so that a proper illumination is not had on the work.

It is an object of this invention, therefore, to provide an iron carrying a lamp thereon which preferably is disposed in one end of the handle of the iron.

It is also an object of the invention to provide such an iron with a switch thereon by means of which the heating current can be turned on or off together with a lamp as above described which lamp can be lighted whether the switch is on or off.

These and other objects and advantages of the invention will be fully set forth in the following description made in connection with the accompanying drawings in which like reference characters refer to the same parts throughout the different views and in which

Fig. 1 is a view in side elevation of the iron, portions thereof being shown in vertical section; and

Fig. 2 is a horizontal section taken on line 2—2 of Fig. 1 and shown on an enlarged scale.

Referring to the drawings, a flat or sad iron of the usual shape is shown having the body portion 1. A handle bracket 2 is se-

cured thereto by suitable means such as the headed screws 3 which bracket carries at its upper end the handle proper 4. The bracket 2 is substantially of U-shape and is formed to abut the rear end of the handle 4 and be secured thereto by screws passing through lugs 2^a into the sides of said handle. The forward portion of the handle 4 is shown as passing through one side of bracket 2 at the top thereof, said bracket having a lug 2^b contacting the top of the said handle. The usual connecting cord for the iron is shown as 5 having therein a pair of electrical conductors or wires 6 which terminate at and are secured, respectively, to the screws or contacts 7. A pair of spaced switch arms or contacts 8 engage and are secured, respectively, to the screws 7. Another pair of spaced contacts 9 are provided secured and engaged by the screws 10, said contacts 9 being longitudinally aligned with the contacts 8. The screws 7 and 10 engage in the side of a casing 11 secured to the body 1 of the iron in any customary and suitable manner which casing preferably is detachable from the iron and electrically connected with the heating means (not shown) therein. The contacts 8 and 9 form the stationary members of a switch and are adapted alternately to be connected and disconnected by spaced and movable contacts 12 which are moved by a handle knob 13 adapted to project at one side of the casing 10. Conductors 14 extend from the screws 10 to the electrical heating means in the iron body 1. A coiled wire conduit 15 is shown in part at the outer end of casing 10 which surrounds and is adapted to protect the cord 5. The handle 4 is hollow and at its front end is provided with the shell 16 forming a threaded lamp socket, said shell being secured by small headed nutted bolts to a block 17 of insulating material secured in handle 4. The tip contact for the lamp socket is formed by the headed and nutted bolt 18 disposed centrally of the block 17. Electrical conductors 19 extend from the bolt 18 and one of the bolts securing shell 16, respectively, through the handle 4 and are connected, respectively, at their other ends to the screws 7. A lamp bulb 20 of standard electrical type is shown as inserted in the shell 16 of the lamp socket and a

shade and reflector 21 is disposed above said lamp 20 and secured to the handle 4 by a headed screw passing therethrough and through the lug 2^b into said handle. As 5 clearly shown in Fig. 1, the lamp 20 projects at the forward end of the iron.

In operation the iron will be connected by 10 the cord 5 as usual to a source of electric current. The switch button 13 will be manipulated to supply heating current to the iron. It will be seen that as soon as the cord 5 is connected to the source of current, lamp 20 will be supplied with current and illuminated. It will also be seen that said lamp 15 when screwed into its socket will be illuminated whether button 13 is turned to supply heating current to the iron or to shut off said current. If it is desired to extinguish the lamp 20, this can be done by turning the 20 same slightly in its socket or, if desired, a key socket may be used.

From the above description, it is seen that 25 applicant has provided a simple and efficient structure of iron and one which will have a high degree of utility. The work will be successfully illuminated and at the proper point. The shade 21 will act to efficiently reflect the light onto the work and to prevent an objectionable glare into the eyes of 30 the operator. The heating of the iron can be controlled without going to the fixture to which cord 5 is connected and the lamp 20 can be used as stated whether or not the iron is being heated. The device can be easily and inexpensively made and the improved handle can be easily installed on 35 standard irons. The device has been amply demonstrated in actual practice and found to be very successful and efficient.

40 It will, of course, be understood that various changes may be made in the form, details and arrangement and proportions of the parts without departing from the scope of applicant's invention which, generally 45 stated, consists in the device capable of carrying out the objects above set forth, such

as shown and described and defined in the appended claims.

What is claimed is:

1. An electrically heated flatiron having 50 in combination, a body portion, a handle secured to said body portion, a lamp carried by said handle above the forward end of said body portion, a pair of conductors for said lamp extending therefrom through 55 said handle, heating means for said body, a cord comprising a single pair of conductors adapted to be connected to a source of current and permanently connected to said first mentioned conductors, and a switch at the 60 rear side of said body adapted to be moved to connect and disconnect said last mentioned conductors to and from said heating means, respectively, whereby said iron may be operated from a single lamp socket and 65 said lamp on the iron may be illuminated whether the heating means is connected or disconnected.

2. An electrically heated flatiron having 70 in combination, a body portion, a handle portion secured thereto, a lamp carried by said handle portion and disposed above the front end of said body portion, a single cord comprising a single pair of conductors extending from said iron and permanently 75 connected to a pair of contacts at the rear of said iron, a pair of conductors connected, respectively, to said contacts and to said lamp, a heating means for said body portion, a second pair of contacts, conductors 80 connecting said last mentioned contacts and heating means, and a switch carried by said iron for connecting and disconnecting said pairs of contacts to turn said heating means on and off, respectively, whereby said iron 85 may be operated from a single lamp socket and with a single cord and said lamp may be continuously illuminated with said heating means connected or disconnected.

In testimony whereof I affix my signature.

ARNE B. OSTBY.
